F. J. KALLMEYER.

CASKET HANDLE.

APPLICATION FILED APR. 7, 1919

1,427,603.

Patented Aug. 29, 1922.

UNITED STATES PATENT OFFICE.

FRANK J. KALLMEYER, OF CINCINNATI, OHIO, ASSIGNOR TO THE CRANE & BREED MANUFACTURING COMPANY, OF CINCINNATI, OHIO, A CORPORATION OF OHIO.

CASKET HANDLE.

1,427,603.

Specification of Letters Patent. Patented Aug. 29, 1922.

Application filed April 7, 1919. Serial No. 288,105.

To all whom it may concern:

Be it known that I, FRANK J. KALLMEYER, a citizen of the United States, residing at Cincinnati, in the county of Hamilton and 5 State of Ohio, have invented certain new and useful Improvements in Casket Handles, of which the following is a specification.

It is the object of my invention to provide 10 new and improved means for connecting the bar with the arm of a casket handle, my invention consisting in novel means whereby the handle-bar is firmly secured in the openings of the arms of the casket handle by 15 pressing a portion of the metal of the wall of the opening of the arm, and especially of the reenforce-bar in the arm, into the surface of the bar, so as to firmly secure the bar and arms together and prevent relative longitudinal movement and also turning movement 20 between the bar and the arms.

The invention will be further readily understood from the following description and claims, and from the drawings, in which lat- 25 ter:

Fig. 1 is a front elevation of a casket-handle, embodying my invention, the casket-handle being partly broken away.

Fig. 2 is a rear elevation of the same.

30 Fig. 3 is a vertical cross-section of the same, taken on the line 3—3 of Fig. 2, showing the bar and arm in raised position in full lines, and in lowered position in dotted lines.

Fig. 4 is a longitudinal section detail, 35 taken on a line corresponding to the line 4—4 of Fig. 3.

Fig. 5 is a perspective view, showing a detail of the handle, and showing the arm thereof as being secured to the bar; and,

40 Fig. 6 is a detail of the punching tool.

11 represents the lug of the casket handle. The lug is attached to the casket, a portion 45 of the wall of which is exemplified at 12, in any suitable manner, as by means of screws 13. The lug may be of suitable material and is usually constructed of metal, either being formed up out of sheet metal, or as a casting out of so-called white metal, which is comparatively soft metal adapted to be conveniently cast into the various ornate forms of 50 lugs of this character.

Arms 15 are pivoted to the lug, as by means of pivot-pins 16 extending through holes in said arms and in wings 17 extending 55 from the lug 11 at the respective sides of said arms. The arms are exemplified as re-

spectively comprising a body 20 cast out of a suitable relatively soft metal, usually known as white metal, adapted to be conveniently cast for receiving the proper contours and shapes in which arms of this character are usually formed. The arms are subjected to great stresses when carrying the casket and its contents, and I preferably provide a reenforce-plate 21, preferably of 60 sheet-steel, which is imbedded in the cast metal of the arm.

The arm is provided with an opening 24 in which the bar 25 is received. This opening is formed by the wall of the relatively 70 soft metal of the casting, in which the wall of the reenforce-plate is imbedded. These walls surround the bar. The reenforce-plate is preferably a more ductile metal than the soft metal, which latter is more brittle. 75

The bar is preferably formed by a sheet-metal shell 31, in which there is a core 32, for instance of wood. The bar may be provided with suitable tips 33, suitably secured to the ends of the bar. 80

The rear or bottom stretches 35, 36, of the walls of the openings in the casting and reenforce-plate of the arm, are preferably so arranged that the inner faces of said stretches are exposed to the bar. These 85 stretches are the rear stretches when the arms and bar are in normal depending relation, and the bottom stretches when the arms and bar are laterally extended for carrying the casket. 90

It is essential in casket handle construction, that a firm connection be provided between the bar and the arms, for the reason that the weight of the casket and its contents is often very great, and a safe carrying of 95 the casket demands that a rigid and firm connection be had between the bar and the arms, which will prevent lengthwise shifting of the bar in the arms, and also turning of the bar in the openings in the arms. Such 100 connections have heretofore been attempted by separate attaching means.

I have provided simple and efficient means whereby a firm connection is accomplished between the arms and the bar without the 105 employment of additional attaching means. For this purpose I bend the metal of the wall of the opening in the arm, into the surface of the bar, accomplished, in the present instance, by punching a portion or portions 110 of the rear or under stretch of the wall of the opening in the reenforce plate into the

bar in said opening, so that the inner face of said portion or portions of said stretch will be imbedded in the bar, or pressed into the outer surface of the bar, so as to extend below or into the normal plane of said surface.

This may be accomplished by means of a suitable punching tool 41, having a punching or indenting surface 42, which is roughened or preferably ribbed as shown at 43, 10 for preventing slippage between said tool and the metal of the stretch, the said indenting surface being sufficiently long to extend entirely across the rear or under stretch 36 of the wall of the opening in the reenforce-plate. The punching may be accomplished by holding the punching tool over said stretch while the other side of the arm and bar is suitably supported so as not to injure the finish or surface of said arm or 20 bar, as on a support 44, cushioned by a suitable pad 45, the tool being struck a blow of sufficient force, as by a hammer, indicated at 46, for forcing the metal of the stretch of the wall of the opening of the reenforce-plate into the sheet metal of the bar, and thereby indenting the latter, for having a protuberance or protuberances 47 in the said inner stretch formed by the blow received in an indentation or indentations thereby 30 made in the metal of the bar, the inner surface of the sheet metal of the bar thereby simultaneously forming a protuberance or protuberances 48, indented and received into an indentation or indentations 49 formed 35 simultaneously by said blow in the core of the bar. The punching may be accomplished in a suitable press. The protuberances and indentations form walls by displacements of material, and these walls coact to prevent 40 movements in all directions between the wall of the opening in the arm and the bar, including its shell and core, especially lengthwise of the bar as shown in Figs. 4 and 5, and crosswise of the bar as shown in Figs. 45 3 and 5.

The indenting of the stretch of the reenforce-plate is preferably accomplished, in the present exemplification, in such manner as to force the metal of said stretch 36 inwardly relatively to the metal of the rear or bottom stretch 35 of the comparatively soft-metal casting, accomplished by providing said wall 35 of the comparatively soft-metal casting with holes 51, through which the punching end of the punching tool is received against the stretch 36, the inner surface of the sheet-metal stretch being presented to the bar for the purpose of indenting the latter.

60 The sheet-metal shell of the bar is preferably provided with longitudinal outer grooves 53, forming inwardly extending longitudinal beads. The beads are preferably received in longitudinal grooves 54 in the

core. The protuberances 47, 48, are preferably received in these grooves. 65

By means of my invention the arm, sheet-metal shell of the bar, and the core of the bar are simultaneously fixed together so as to prevent movements between the bar and its core and the arms of the handle in directions lengthwise of the bar, and also about the axis of the bar, the employment of additional attaching means is avoided, and a pleasing appearance is presented. 70 75

Having thus fully described my invention, what I claim as new and desire to secure by Letters Patent, is:

1. In a casket handle, the combination of a pivoted arm, said arm having an opening, 80 and a bar received in said opening, a portion of the wall of said opening indented inwardly into said bar by pressure to form a protuberance at the inner face of said portion, and an indentation at the outer face 85 of said bar with the wall of said indentation surrounding said protuberance.

2. In a casket handle, the combination of a pivoted arm having an opening, and a bar comprising a core and a sheet-metal shell 90 surrounding said core, said bar located in said opening, a portion of the wall of said opening indented inwardly into said shell by pressure and a coincident portion of said shell indented inwardly into said core by 95 pressure to form a protuberance at the inner face of said portion of said arm and an indentation at the outer face of said shell and an indentation at the outer face of said core, 100 with the walls of said respective indentations surrounding said protuberances respectively.

3. In a casket handle, the combination of a pivoted arm comprising a reenforce-plate 105 of relatively hard metal and a casting of relatively soft metal about said reenforce-plate, said reenforce-plate and said casting having an opening therein with said reenforce-plate having an integral wall completely surrounding said opening, and a bar received in said opening, a portion of said wall provided with an inwardly extending protuberance extending inwardly into said bar to form an indentation in said bar, and said casting provided with a recess at said protuberance outwardly from said protuberance, with the wall of said indentation surrounding said protuberance whereby to fix 115 said bar in said arm. 120

In testimony whereof, I have hereunto signed my name in the presence of two subscribing witnesses.

FRANK J. KALLMEYER.
